UNITED STATES PATENT OFFICE.

JAMES SCRIPPS BOOTH, OF DETROIT, MICHIGAN.

DESIGN FOR A MOTOR-CYCLE FRAME.

41,729.

Specification for Design.

Patented Aug. 29, 1911.

Application filed February 26, 1910. Serial No. 546,205. Term of patent 14 years.

To all whom it may concern:

Be it known that I, JAMES SCRIPPS BOOTH, a citizen of the United States of America, residing at Detroit, in the county of Wayne and State of Michigan, have invented a certain new, original, and ornamental Design for Motor-Cycle Frames, of which the following is a specification, reference being had to the accompanying drawing, forming part thereof.

In the drawings, Figure 1 is a side ele-

vation of a motor cycle frame showing the new design; Fig. 2 is a plan view of the same; and Fig. 3 is a perspective view.

I claim:

The ornamental design for a motorcycle frame, as shown.

JAMES SCRIPPS BOOTH.
